UNITED STATES PATENT OFFICE.

HANS P. JENSEN-BÄRLUNDD, OF LISBON, PORTUGAL.

VARIABLE-PITCH PROPELLER.

1,380,305.

Specification of Letters Patent. Patented May 31, 1921.

Application filed January 31, 1919. Serial No. 274,342.

To all whom it may concern:

Be it known that I, HANS P. JENSEN-BÄRLUNDD, a citizen of Denmark, residing at Lisbon, Portugal, have invented certain new and useful Improvements in Variable-Pitch Propellers, of which the following is a specification.

The present invention comprehends generally improvements in propellers and more particularly relates to a variable pitch propeller.

It is the primary aim and object of the invention to provide a propeller of the above mentioned character the construction of which is novel in form and designed to be used preferably in connection with flying machines though it is also well adapted for use on ships in the nature of a paddle wheel while the blades are automatically adjustable to insure of an effective propelling action.

As an additional and equally important object this invention contemplates the provision of a device of the above mentioned character designed in the form of a rotatable frame in which the blades are journaled for oscillatory movement while acting in conjunction with the blades in the improved means for automatically adjusting the pitch of the blades in relation with and during the rotation of the frame.

As a further improvement, the present invention embraces the provision of a propeller of the above mentioned character wherein manually operable means is employed and designed to coöperate with the pitch adjusting means of the blades for insuring of an effective steering and stabilizing of the machine when in flight.

More particularly, this invention consists in the provision of a propeller of the above mentioned character designed so that the stream of air leaving the propeller is guided into the desired direction thereby insuring of the raising of the machine direct from the ground and the landing of the machine in close places, at the same time obviating the usual wing construction of an aeroplane while the weight center of the machine is preferably placed under the propeller shaft to make the machine self-stabilizing.

It is a more specific object of this invention to provide a device of the above mentioned character wherein the means for automatically adjusting the pitch of the blades

or wings is so constructed that during one-half revolution of the propeller, the wing planes will act without waste power on the atmosphere to insure an effective propelling action, while during the other half revolution, the blades or wings will be positioned so as to produce a minimum resistance against the motion of the propeller.

The improvements in the details and arrangement of parts will be apparent from an inspection of the accompanying drawings, in connection with the specific description hereinafter contained, and wherein the preferred embodiment of the invention is disclosed for the purpose of imparting a full understanding of the invention.

The invention is clearly illustrated in the accompanying drawings, in which:

Figure 1 is a top plan view of an aeroplane with two sets of propellers attached thereto,

Fig. 2 is a top plan view of another machine with only one set of propellers applied thereto,

Fig. 3 is an enlarged side elevational view looking toward the rear of the propeller on the right side of the body of the machine,

Fig. 4 is another elevational view looking toward the end of the shaft, of the left propeller,

Fig. 5 is a diagrammatic view showing the positions assumed by the blades or wings during rotation of the same,

Fig. 6 is an enlarged transverse sectional detail through one of the blades or wings,

Fig. 7 is an enlarged side elevational detail partly in section of the means for automatically adjusting the pitch of the blades,

Fig. 8 is an elevational detail of one of the blades or wings and the means for mounting the same,

Fig. 9 is a detail of the steering means,

Fig. 10 is an enlarged fragmentary elevational detail of the bearing support for the blades or wings, and

Fig. 11 is an enlarged longitudinal sectional detail of the propeller shaft or hub.

Similar characters of references are employed in all of the above described views, to indicate corresponding parts.

Referring now, more particularly, to the accompanying drawings, especially Figs. 1 and 2, there are provided two types of aeroplanes on which are mounted the im-

proved propellers designated in their entireties by the numeral 1. The aeroplane body shown in Fig. 1 is desirably of a heavy type being fitted with two sets of propellers 5 arranged in opposed relation and positioned on opposite sides of the body, the shaft of the forward propellers being extended transversely of the body of the aeroplane while the rear propeller shafts are arranged longitudinally 10 constituting carrying propellers for coöperating with the forward propelling propellers. Side and balancing rudders 2 and 3 respectively are associated with the tail end of the body shown in Fig. 1. The body shown in Fig. 2 has the engine 4 positioned transversely thereof and desirably medially of the ends and in this form or type of machine, only one set or pair of propellers 1 are employed being positioned so 15 that the shafts which are connected with the ends of the shaft are arranged transversely or laterally of the opposite sides of the body while coacting therewith are the side rudders 5, it being unnecessary to employ balancing rudders, since this type of machine 20 is self-stabilizing and owing to the peculiar construction of the propellers, as will hereinafter become apparent, it is unnecessary to employ the customary sustaining planes 25 as on the usual type of aeroplane.

In reducing the propellers 1 to practice, each may be said to consist of a rotatably mounted sectional shaft generally designated by the numeral 6, shown in detail in Fig. 11, the inner sections 7 of which are adapted for connection with the ends of the shaft of the engine 4 being also journaled through a bearing bracket 8 in the side of the aeroplane body and connected at its outer end with the outer sections 9 as by detachable fasteners 10. The respective ends of the outer sections are formed with flanges 11 which form the hubs of spaced wheels generally designated by the numeral 11'. These wheels consist of inner rims 12 and outer rims 13, the inner rims being connected to the flanges or hubs 11 by means of bracing spokes 14 while the rims 12 and 13 are maintained in spaced surrounding relation with respect to each other through the instrumentality of radially disposed bearing supports generally designated by the numeral 15.

In the present construction, preferably four of the bearing supports 15 are employed and each preferably consists of a radially disposed stationary spoke 16 the rigidity of which is increased with respect to the rim by braces 17. Opposed to the spoke 16, is a detachable spoke 18 while mounted between the spokes 16 and 18 are a plurality, preferably three, radially arranged bearing blocks 19 removably fastened in properly adjusted positions by suitable fasteners 20. The supports 15 in one wheel are arranged

in opposed relation to the supports in the other wheel as are the bearing blocks 19 so that the latter may have journaled therein a journaling portion 21 of the transversely extending sectional shaft 22, said portions 21 being preferably positioned between and detachably connecting the intermediate section and the end sections of the shaft 22, the construction being indicated in Fig. 8. Sectional wings or blades 23 are carried by the intermediate and end sections of the shaft 22. Also, carried by the projecting portion of one of the journaling portions 21, is a worm gear 24 for a purpose that will presently appear. By this construction and arrangement of parts the blades or wings 23 of the propeller will be arranged radially of the supporting wheels while the intermediate section will be positioned between the wheels and the end sections of the said blades or wings will extend beyond the opposing faces of the wheels as shown in Figs. 2 and 4.

With a view toward providing the improved means for automatically adjusting the pitch of the blades or wings 23 in timed relation with and during the rotation of the shaft 6, a disk 25 is loosely disposed about the inner section 7 of the shaft 6 being arranged eccentric thereof and provided in its outer face with an annular groove 26 positioned eccentrically of the shaft 6 having recesses 27 in the bottom thereof for a purpose that will appear. Opposed pairs of radially extending shafts 28 are now employed and are journaled in the radially alining bearings 29 and 30 carried respectively by the adjacent flange or hub 11 and the alining support 15, being illustrated in Fig. 4. Toothed cam wheels 31, having teeth 32, are carried by the inner ends of the shaft 28 and operate in the groove 26. Inasmuch as these shafts are mounted on the wheels and are moved therewith, the disks 25 being stationary with respect thereto, the interengaging cam wheels 31 and groove 26 consequently insure the imparting of a rotary as well as a reciprocatory motion to each of the shafts 28 during the rotation of the shaft 6. The outer ends of the shaft 28 are in turn formed with worms 33 which mesh with the worm wheels 24 carried by the adjacent wing or blade shafts 22 to ultimately insure of an oscillation of the blades or wings 23 in timed relation with the wheels 11. In connection with the foregoing, it is preferred that the eccentricity of the groove 26 be equal to one-eighth of the circumference of the gear wheels 24 while the pitch of the worms 33 should be proportioned so that the worm wheels 24 will make a half revolution for every revolution of the wheels 11', thereby simultaneously rotating and reciprocating the shaft 28 to consequently automatically 130

cally vary the pitch of the blades 23 in timed relation with and during the rotation of the wheels throughout the flying.

As intimated, improved gearing means 5 has been provided for acting in conjunction with the propeller blades to enable the driver to maintain complete control of the machine. In reducing this feature of the invention to practice, sleeves 34 are formed 10 with the disk 25 and are loose on the shaft 6 of opposing propellers 1. Worm wheels 35 are connected to the sleeves and mesh with worms 36 formed on vertically disposed and rotatable shafts 37. Beveled 15 gears 38 are carried by the lower ends of the shafts 37 and mesh with other bevel gears 39 carried on the outer projecting ends of transversely extending shafts 40 journaled in the body of the aeroplane. Independent 20 control of one of the opposing propellers 1 is effected by a shaft 41 journaled in supporting brackets 42 in the body of the aeroplane and carrying at its inner end a bevel gear 43 which meshes with a beveled gear 25 44 carried by the adjacent shaft 40. A hand wheel 45' is mounted on the outer end of the shaft and positioned in proximity to the driver for rotating the shaft 41 to adjust the disk 25 on the adjacent propeller, the 30 corresponding motion being transmitted of course by the gears 35, 36, 38 and 39, carried respectively by the adjacent sleeve 34 and shafts 37 and 40, the arrangement being clearly indicated in Fig. 9. A sleeve 45 is 35 disposed about the shaft 41 serving to support a hand wheel 46 and carrying at its inner end a bevel gear 47 which meshes with another beveled gear 48 on the other shaft 40 so that when the wheel 46 is turned, the 40 sleeve 45 will be rocked or moved independently of the shaft 41 to impart movement to the shaft 40 and thence to the disk 25. Ordinarily, it is only necessary for the driver to maintain his hands on the wheel 45 to prevent accidental movement of the disk 25 and in consequence accidental varying of the pitch of the blades. At times, however, it is necessary for the driver to adjust the disk 25 to consequently vary the 50 pitch of the blades so that the machine will assume the desired course, it being the principle of the propeller to maintain the blades 23 at such pitch in the wheels that during a one-half revolution of the wheel 11' or 55 the propeller proper the blades will act without waste of power to effectively engage the air for insuring a propelling action, while during the other half turn, the blades will be at such a pitch that only a 60 minimum resistance will be occasioned against the revolving motion of the propeller, as is apparent.

In the diagrammatic view, Fig. 5 of the drawings, there is shown a pair of the opposing blades 23 and the positions assumed

thereby, in dotted lines, during a half revolution of the wheel 11'. The positions are indicated by the letters A, B, C, D, E, F, G, and H. When one of the blades 23 moves from the position A to E, the shaft 28 which is mounted on the wheel 11' and has its cam wheel 31 connecting with and guided by the groove 26 is partially rotated a one-quarter turn correspondingly partially rotating the gear wheel 24 and the said blade. 70 Also, by moving in its own longitudinal direction an extra one-quarter turn is imparted to the said wheel 24 and the said blade 23, so that the blade will be ultimately given a one-half rotation. Now the other 75 blade 23 will move from position E to A, being affected by the adjacent shaft 28 which has its cam wheel 31 arranged in the groove 26 and its worm 33 meshing with the adjacent gear wheel 24, whereby the 80 worm 33 is simultaneously rotated a quarter turn, tending to rotate the gear wheel 24 a quarter turn, and reciprocated in a direction and to a sufficient distance to rotate gear wheel 24 a quarter turn in the opposite 85 direction, so that the position of gear wheel 24 relatively to wheel 11' remains unchanged, as is apparent. It is to be understood that the opposed radial series of blades or wings operate correspondingly. It is 90 also to be understood that by adjusting the wheels 45 and 46, the positions of the blades or wings may be varied relative to the rotating wheel 11', as is apparent.

In operation, the disk 25 being set as the 100 shaft 6 carrying the wheel 11' rotates, the shafts 28 which are slidably and rotatably mounted on the wheel 11' are given such movement by the toothed cam wheels 31 operating or meshing with and guided by 105 the groove in the relatively stationary disk and having their wormed portions 33 meshing with the worm wheels on the shafts 22 consequently insures the automatic varying of the pitch of the blades 23 on the said 110 shafts 22 in timed relation with and during the rotation of the said wheel 11'.

It is believed in view of the foregoing description that a further detailed description of the operation of the invention is entirely 115 unnecessary. Likewise, it is believed that the advantages of the invention will be readily apparent.

As many changes could be made in the above construction and many apparently 120 widely different embodiments of this invention could be made without departing from the scope thereof, it is intended that all matter contained in the above description or shown in the accompanying drawings shall 125 be interpreted as illustrative and not in a limiting sense. It is also to be understood that the language used in the following claims is intended to cover all of the generic and specific features of the invention herein 130

described and all statements of the scope of the invention, which, as a matter of language, might be said to fall therebetween.

Having thus fully described my invention, 5 what I claim as new, and desire to secure by Letters Patent, is:

1. In combination with a propeller, a rotatable shaft, a frame carried by and rotating with the shaft, oscillating blades mounted in the frame, members slidably mounted on the frame and operably connected with the adjacent blades for rocking the blades, means on the shaft having eccentric connection with each of the members for sliding and rotating the members to consequently oscillate the blades to vary the pitch thereof in timed relation with and during the rotation of the shaft.
2. In combination with a propeller, a rotatable shaft, a frame carried by and rotating with the shaft, oscillating blades mounted in the frame, members slidably mounted on the frame and operably connected with the adjacent blades for rocking the blades, means on the shaft having eccentric connection with each of the members for sliding and rotating the members to consequently oscillate the blades to vary the pitch thereof in timed relation with and during the rotation of the shaft, and manually operable means in connection with the last mentioned means for adjusting said means.
3. In combination with a propeller, a rotatable shaft, a frame carried by the shaft including spaced wheels, a series of blades arranged transversely of the wheels and having their longitudinal axes positioned radially of and journaled in said wheels, a disk loose on the shaft, and a plurality of

shafts slidably and rotatably mounted on one of the wheels and operably connected to the adjacent blades, means whereby said shafts on the wheel are reciprocated and rotated by the disk for varying the pitch of the blades in timed relation with and during the rotation of the frame.

4. In combination with a propeller, a shaft, a frame carried by the shaft, a plurality of oscillating blades in the frame, a disk loose on the shaft, a plurality of shafts slidably and rotatably connected to the frame and operatively connected to the adjacent blades and also operatively connected to and operated by the disk during the rotation of the frame to consequently vary the pitch of the blades, and means whereby said shafts are reciprocated and rotated by the disk for preventing movement of the disk yet at the same time serving as a means for adjusting the disk when desired.

5. In combination with a propeller, a rotatable shaft, a frame carried by the shaft and including spaced wheels, a series of blades positioned transversely of the wheels and having their longitudinal axes journaled in the wheels, a disk loose on the shaft and having a groove therein eccentric to the shaft, a plurality of shafts slidably and rotatably connected to one of the wheels and operatively connected at their outer ends to the adjacent blades, gears on the inner ends of the shafts to insure of the rotation and sliding of the shafts to consequently vary the pitch of the blades during and in timed relation with the rotation of the frame.

In testimony whereof I affix my signature hereto.

HANS P. JENSEN-BEÄRLUNDD.
